CARL A. BRAUN, OF TOLEDO, OHIO, ASSIGNOR, BY MESNE ASSIGNMENTS, TO STEEL AND TUBES, INC., OF CLEVELAND, OHIO, A CORPORATION OF OHIO

PRESS CUT-OFF

Application filed November 23, 1927. Serial No. 235,283.

This invention relates to apparatus for severing rapidly traveling metallic articles such as tubing and the like, into predetermined lengths in which the severing mechanism is moved along by and with the traveling article. It is particularly concerned with such apparatus in which the severing mechanism is in the form of a punch press with certain parts constructed for bodily movement parallel to the line of travel of the articles being severed.

One of the main objects of the invention is to construct a device of the character described which is capable of cutting a tube into parts of uniform, predetermined length as rapidly as it is formed commercially by any tube forming method and in which the advantages of a punch press are combined with the advantages of propulsion by the articles to be severed.

Another object is to construct a device of the class described which includes a simple cut off apparatus free from the disadvantages of moving parts of great weight and a multiplicity of complicated actuating devices requiring a high degree of accuracy in adjustment and operation.

A further important object is to construct a device of the character described in which means is provided for utilizing the thrust of the traveling article to be severed for actuating the severing mechanism while preventing distortion or wrinkling of the tube at the severed end and undue friction between the end of the uncut tube and the cutting blade during the return stroke of the latter.

Other objects ancillary to the foregoing will appear and be pointed out hereinafter.

Although this invention is applicable to articles including solid and hollow forms composed of various metallic materials and of various cross-sectional configurations, it has been found highly advantageous in the manufacture of cylindrical steel tubing. By suitably constructing the moving parts of a device embodying my invention, tubes of such materials and configurations and having gauges and diameters ranging thruout the entire field now covered, for example, by commercial electric welding, can be severed into

pieces of uniform predetermined length as rapidly as formed. Moreover, with such suitable parts, tubing traveling at any speed within the range now common, for example, in commercial electric welding, can be severed into pieces of uniform predetermined length; and the lengths of such pieces can be varied over substantially the entire range of commercial tube lengths, provided however that with the shorter lengths the speed of travel of the tubing is suitably selected.

In the drawings accompanying and constituting a part of this specification

Figures 1 and 2 are respectively top plan and side elevational views of one form of apparatus embodying my invention and showing fragmentarily a part of a welding machine.

Figures 3 and 4 are respectively fragmentary right side and rear end elevations of the cut off mechanism shown in Figures 1 and 2.

Figure 5 is a vertical, fragmentary, sectional view taken on line 5—5 of Figure 4.

Figure 6 is a horizontal sectional view taken on line 6—6 of Figure 4;

Figure 7 is a vertical, view partly in section taken on line 7—7 of Figure 5 but showing the press in open position that is at the end of the stroke opposite to that shown in Figure 5.

Figure 8 is a wiring diagram showing the circuits, breakers, solenoid, etc., as employed in the illustrated device.

In the foregoing figures I have illustrated one form of apparatus embodying my invention. This apparatus is shown arranged in operative position with respect to an electric tube welding machine with which the said apparatus may advantageously be used, though, it will be understood that it may be employed with tubing formed by other means and welded, unwelded, butted or seamless. Previously formed articles may thus be cut by apparatus embodying my invention, it only being necessary to propel the uncut article forwardly with sufficient force to actuate the cut-off mechanism constituting my invention.

In the drawings, A designates a fragmentary part of an electric tube welding machine

from which welded tube B is propelled to the apparatus C embodying my present invention, in which the tubing B is severed into pieces of predetermined uniform length. It will be understood that any preferred form of tube welding apparatus may be used as the apparatus designated by A, for example, such apparatus as is shown in the patent to Lloyd No. 1,027,865 issued May 28, 1912, or in the patent to Johnston No. 1,388,434 issued August 23, 1921. The tubing B formed by this welding machine A is delivered therefrom in continuous or relatively long lengths. Suitable rolls in the welding machine propel the tubing forwardly so that when it reaches the apparatus C it is being positively propelled from the welding apparatus A at a certain fixed speed and with considerable force. The apparatus C about to be described in detail is so constructed that it may be actuated by the traveling tube even when the tube is composed of thin gauge metal and has a small diameter. With such tubing less force is required to produce buckling or bending of the tubing than with heavier gauge metals and larger diameter tubes.

Apparatus C, as shown herein, may be briefly described as comprising a tube-actuated, punch press cut-off mechanism and certain associated parts are actuated by and move synchronously with the tubing that is to be severed. The parts moved by the tubing are of fairly light weight, so designed as to move freely and without unnecessary friction and are actuated wherever necessary by simple, substantially positive means controlled directly by movement of the tube to be severed without the interposition of complicated control mechanism and in certain instances actuated directly by the movement of the tube B.

More particularly apparatus C comprises, in the embodiment here shown, a punch press having a base portion 2, a table 3 and upright portions 4 carrying a crank-shaft 5 to which it attached a reciprocable press-head 6 and a flywheel 7 together with clutch-mechanism of the ordinary type (not shown in detail) by which the crankshaft may be tripped so that it will make one complete revolution. The head 6 is fitted with a forwardly extending plate 9 provided with a dove-tailed slide 10 in which die-closing member 11 is mounted for movement relative thereto. The die closing member 11 consists of a base portion 11a slidably engaged in the slide 10 and two depending portions 11b each fitted with hardened steel wedges 12 for a purpose presently to appear. The member 11 also carries depending from its portion 11a, a knife 13 which, in this instance, is constructed for the severing of tubing and consists of a blade of flat material terminating in a pointed end 13a suitably shaped to cut a tube without materially distorting or bending the tube.

The press table 3 is provided with a top 14 and has on its upper surface elongated holes 15 to accommodate the portions 11b of the die-closer when the member 11 is in positions at or near the lower end of their stroke. The table 14 is also provided with a central opening or groove 15a in its top surface in which rods 16a and 16b are mounted to reciprocate. These rods, which will presently be described in more detail, are secured within the recess 15a as by means of nuts 16c and 16d or the like, to depending lugs 17a and 17b respectively integral with a carriage 18 slidable on top 14 and provided on opposite sides thereof with fixed brackets 19 suitably spaced apart to engage opposite sides of the depending portions 11b of the die-closer 11. By means of these brackets 19 longitudinal movement of the rods 16 may be transmitted by way of the lugs 17a and 17b to carriage 18 and to the die-closer 11, while at the same time the die-closer 11 may be permitted to move vertically with respect to the carriage 18. The carriage 18 carries between the brackets 19 a suitable member, in this case comprising dies or clamps slidable crosswise of the carriage 18 in suitable guide-ways, adapted to grip or clamp around tubing B which is to be severed. These dies or clamps preferably comprise two pair of dies 21 and two die holders 22, the dies being suitably secured, one pair in each of the die holders 22. The holders 22 are each slidable on the carriage 18 in a horizontal plane transversely of the line of travel of tube B and are provided with a roller 23 which is mounted to revolve about a shaft 24 which has a bearing in a pair of eccentric, end-supporting bushings or bearings 25 each flanged at one end as at 26. Each of the flanges 26 is perforated at intervals to receive set screws or similar positioning means 28. These bushings 25 are rotatably mounted in the die-holders 22 and by means of the cap screw 28 can be disposed in any desired position as regards the outer cam or eccentric surface 27 thereof which as will be readily understood from Figures 6 and 7 will result in positioning the roller shaft 24 closer to or more remote from the holders 22. These rollers 24 are disposed in alignment with the portions 11b of member 11 and are engaged by the wedges 12 so that when the die-closer 11 is moved downwardly the wedges 12 engage with the rollers 23 thereby sliding the die-blocks 22 and dies 21 into gripping engagement about a tube B that is to be severed. When the portions 11b move out of engagement with the rollers 23, the springs 29 carried by dies 21 expand and move the dies 21 and blocks 22 apart as shown in Figure 7. It will be understood that tubing and similar articles of various sizes and cross sectional configurations may be accommodated by merely substituting dies of the proper size 130.

and shape for dies 21 above described. Likewise by suitably adjusting the bushings 25 in the blocks 22 the force with which the dies are clamped about the tube B or other article may be varied. The dies 21 of each pair are shown spaced apart from each other in the line of travel of the tube B by an amount slightly greater than the thickness of the knife 13, and holders 22 have vertical slots 22a (Figure 7), of such width that knife 13 is permitted to move freely between the dies 21 and through the holders 22.

The rod 16a which is suitably supported at its rear end as by a pedestal carries a target 30 adjustably secured thereto at any point corresponding to the length of severed tubing desired and is also provided at a point suitably selected with respect to the table 14 with a cam-engaging projection 31 which is positioned to ride up on the cam 32 fixed to the rear end of the table 14 so that when the rod is moving toward the front end of the machine the member 31 will engage the cam 32 and turn the rod 16a so that the target will assume such a position that it will be engaged by the advancing tube B, as in Figures 1, 2 and 3.

The rod 16a and target 30 are actuated out of position in front of the tube B by means 30 of a projection here shown in the form of a telescoping rod 33 depending from the rearward end of plate 9 and engageable with member 31. As the press-head 6 descends the rod 33 engages with the member 31, first compressing the spring 33a in the rod 33, and finally rotating the rod 16a.

The press-head 6 carries a laterally projecting arm 34 which slidably receives a rod 35 adjustable as to length which is attached at its lower end to a crank 36, (Figure 7) secured to the moving element of a multiple-way, air valve 37. The rod 35 is provided at a suitable point with a V-shaped recess 38 into which a plunger 39 carried by the member 34 may be spring pressed. The moving element of the valve 37, in addition to carrying the crank 36, also carries a lever 40 which is engaged in certain position by a spring-pressed rod 41 carried by the carriage 18.

The valve 37 is connected with a suitable source of fluid under pressure, for example, compressed air, and is connected by suitable connections 42 and 43 to opposite ends of a cylinder 44, suitably disposed at the front end of the machine. The piston rod 45 is operatively associated at its rear end for lost motion with a suitable yoke 46 carried by the rod 16b.

The carriage 18 carries at one side thereof a pivoted arm 47 spring-pressed by spring 48 at one end and having a roller engaging face 49 at the other end to engage with a roller 50 which is attached to the contact-making member of an electrical switch 51 connected with the windings of a solenoid 52.

The upright 4 of the press carries a control or switch box 53 containing the remaining portions of the wiring shown in Figure 8. Certain leads from this box are connected to a switch 54, also carried by upright 4, and have a contact-making member equipped with a roller 55 positioned to engage with an adjustable member 56 carried by the head 6. A main line switch 59 inserted in the power line ahead of the boxes 51 and 53 controls the flow of electric current to these boxes.

The operation of the apparatus above described is substantially as follows:

When the parts of apparatus C are in the positions shown in Figures 1, 2 and 3 tubing B to be severed is passed rearwardly through the propelling rolls of machine A and between dies 21 until it strikes target 30. Thereafter it continues to move rearwardly at the same speed, carrying with it target 30, rods 16a and 16b, carriage 18, head plate 9 and the parts between plate 9 and carriage 18. As the carriage 18 moves rearwardly on the table 14 the arm 47 engages the roller 50 thereby closing the switch 51 (Figure 8) and completing the circuit from the main power line X through the switch 51 and magnet Y to the other branch Z of the main power line. The magnet Y is thus energized and attracts the knife blades 60 and 61 in controller box 53 whereupon current flows from X thru 60, switches 51 and 54 and magnet Y and also thru 60, solenoid 52 and 61. This solenoid 52 is provided with an iron core 57 slidable therein and secured at one end of a pivoted arm 57a to the other end of which the trip rod 58 of clutch 8 is attached. When the solenoid 52 is energized, the core 57 is attracted, thereby moving the arm 57a about its pivot and actuating the trip of clutch 8 thus operatively connecting the flywheel 7 with the crankshaft 5, thereby setting the head 6 in motion downwardly. The contact of arm 47 with roller 50 is momentary or of relatively short duration but continues sufficiently long for the blades 60 and 61 to be actuated into closed position.

After the gears are meshed and the head 6 has moved down some distance, the member 56 moves roller 55 and breaks the connection in switch 54. As soon as the arm 47 moves beyond the roller 50 the electrical connection through switch 51 is broken and as soon as roller 55 is actuated by member 56 switch 54 is opened. Thereupon magnet Y is deenergized and switches 60 and 61 are opened as by their own weight, springs or the like (not shown) and then the solenoid 52 is deenergized. This permits the arm 57a to resume its original position due to the weight of core 57 and through coincident movement of trip rod 58, insures a disengagement of the flywheel 7 and crankshaft 5 after a single complete rotation of the latter. The head 6 in moving downward brings the wedges 12 of

portions 11b of die closer 11 into contact with the rollers 23 causing rotation of the rollers and movement of the dies 21 into gripping contact with the tube B. Until the tube B is thus gripped by the members 21 all laterally movable parts of the device C are actuated solely by the tube B pushing against the target 30. As soon, however, as the members 21 grip around the tube the application 10 of moving force by the tube B to the laterally moving parts of the device C is largely transferred to and concentrated at the dies 21. As the press-head 6 continues to move downwardly after closing the dies 21, the knife 13 contacts with the top of the tube B and cuts down through the tube thereby severing the same intermediate the ends of the dies 21. The telescoping rod 33 is of such a length that while it contacts with member 31 early in 20 the down stroke of head 6 it does not exert sufficient force on member 31 to rotate rod 16a until after the knife 13 has severed the tube B, this turning movement carrying the target 30 away from the end of the tube B.

25 As the press-head 6 reaches or rises from the lower end of its stroke the plunger 39 seats in the recess 38 of rod 35 so that when the press-head 6 moves upwardly it carries rod 35 with it thereby turning the moving 30 part of valve 37. When the knife 13 clears the top of dies 21, the moving part of valve 37 admits air or other compressed fluid thru connection 42 into the rear end of cylinder 44 with the result that the piston therein is 35 forced forwardly in the cylinder 44 carrying with it the rods 16b and 16a and the laterally moving cut-off parts, thereby restoring the same to their initial or starting position. It will be understood, however, that 40 this forward movement of the rods 16b and 16a does not take place until the wedges 12 of the member 11 have cleared the rollers 23 and permitted the springs 29 interposed between the holders 22 to spread the latter 45 apart and release the tube B. The continuous rearward movement of the unsevered portion of the tube B forces the severed portion out of the dies 21, since target 30 is then not in its path, after which it may be delivered by a suitable conveyor, slide or the like or manually to a truck, rack or the like where the severed portions are being collected.

When the head 6 has carried rod 35 up to the point where it is arrested by the stop in 55 the valve 37 engaging the moving element of the valve, the plunger 39 is unseated from notch 38, the head 6 continuing on its upward stroke while the rod 35 remains in its topmost position until the laterally moving 60 parts of device C have reached their extreme forward or initial position. At approximately such time the front end of rod 41 engages lever 40 attached to the moving element of valve 37 and rotates said lever 65 thereby rotating the said element to its ini-

tial or starting position as shown in Figures 5 and 7. Such rotation of the said element cuts off the supply of fluid pressure thru connection 42 to cylinder 44, then opens the exhaust port to allow the fluid in the rear end 70 of cylinder 44 to escape, and finally admits fluid pressure through connection 43 to the cylinder which moves the piston to the rear end of the cylinder which is its initial or starting position.

75 After the head 6 has risen far enough for rod 33 to exert little or no pressure on member 31, this member engages with cam 32 as rod 16a moves forwardly and the cam rotates rod 16a and target 30 into the initial or starting position. As head 6 rises member 56 moves relative to roller 55 and permits the making of contact in the switch 54; and then arm 47 passes beneath roller 50 into 80 position to make contact in switch 51 as 85 aforescribed.

90 It will be understood from the foregoing description and the attached drawings that I have provided a cut-off device that may be characterized as relating to the punch-press type but in which the parts to be moved by the travelling tube to be severed are so light and mounted for such free movement that they offer substantially no hindrance to the free continuous forward movement of the 95 unsevered tube. Moreover, the solenoid and the clutch are not only positively actuated but are positively controlled by means of the switches 51 and 54 so that only one revolution of the press-head is permitted while the 100 tubing is moving, regardless of the speed of travel of the tubing. Rearward movement of all the moving parts of the cut-off device is controlled by movement of the tube B directly and without the interposition of control-devices which require careful adjustment and attention.

105 The device described hereinabove includes a press with a certain length of stroke which determines the positions of the cutter 13, as 110 more or less accurately shown in the drawings. It will be understood, however, that when a press with a shorter stroke is employed the cutter will not extend so far past the tube nor be raised so high thereabove and hence the invention may be adapted to use with tubing traveling at high rates of speed 115 and to the cutting of short lengths.

120 Having thus described my invention so that others skilled in the art may be enabled to practice the same what I desire to secure by Letters Patent is defined in what is claimed:

What is claimed is:—

125 1. Apparatus for severing moving articles comprising means for forcibly impelling in an axial direction an article of indefinite length, in combination with flying cut-off mechanism for cutting successively predetermined uniform lengths from the end of said 130

article without interrupting the movement thereof, said cut-off mechanism including a member movable by and disengageable from the said article, a carriage connected with said member and carrying article clamping dies, an article cutter mounted on said carriage and a stationary device having a reciprocating part initially actuated by axial movement of the carriage and connected to the said cutter to actuate the latter across the line of travel of the article.

2. Apparatus for severing moving articles comprising means for forcibly impelling in an axial direction an article of indefinite length, in combination with flying cut-off mechanism for cutting successively predetermined uniform lengths from the end of said article without interrupting the movement thereof, said mechanism including a member engageable with and movable by the said article, a carriage connected to and movable by said member and carrying article clamping dies, an article cutter movable by and with said carriage, and a stationary press having a reciprocating head connected to the said cutter to actuate the same across the line of travel of the article.

3. Apparatus for severing moving articles comprising means for forcibly impelling in an axial direction an article of indefinite length, in combination with flying cut-off mechanism for cutting successively predetermined uniform lengths from the end of said article without interrupting the movement thereof, said mechanism including a member engageable with and disengageable from and movable by the said article, a carriage movable by said member, an article cutter operatively associated with said carriage for movement with and also relative thereto, and a stationary press having a reciprocating head operatively connected to the said cutter to actuate the same across the line of travel of the article.

4. Apparatus for severing moving articles comprising means for forcibly impelling in an axial direction an article of indefinite length, in combination with flying cut-off mechanism for cutting successively predetermined uniform lengths from the said article without interrupting the movement thereof, said mechanism including a carriage movable in directions parallel of the line of movement of the said article, dies carried by the said carriage for clamping about the said article, a cutter movable across the article intermediate the ends of the said dies, and a stationary device having a reciprocating part operatively connected to the said cutter to actuate the same to sever the article intermediate the ends of the dies.

5. Apparatus for severing moving articles, comprising means for forcibly impelling in an axial direction an article of indefinite length, in combination with flying cut-off

mechanism for cutting successively predetermined uniform lengths from the end of the said article without interrupting the movement thereof, said mechanism including a target disposed in the line of travel of the said article, a rotatable and axially moving rod carrying the said target, a carriage connected to the said rod, article clamping dies carried by the said carriage, an article cutter movable across the line of travel of the article, and a stationary device having a reciprocating part operatively connected to the said cutter to move the same across the line of travel of the said article intermediate the ends of the dies.

6. Apparatus for severing moving articles, comprising means for forcibly impelling in an axial direction an article of indefinite length, in combination with flying cut-off mechanism for cutting successively predetermined uniform lengths from the end of the said article without interrupting the movement thereof, said mechanism including a target disposed in the line of travel of the said article, a rotatable and axially moving rod carrying the said target, a carriage connected to the said rod, article clamping dies carried by the said carriage, an article cutter movable across the line of travel of the article, means to rotate the rod and target out of the line of travel of the article after the cutter has severed the latter, and stationary means carrying reciprocating mechanism for actuating the cutter across the path of the article.

7. Apparatus for severing moving articles, comprising means for forcibly impelling in an axial direction an article of indefinite length, in combination with flying cut-off mechanism for cutting successively predetermined uniform lengths from the end of the said article without interrupting the movement thereof, said mechanism including a target disposed in the line of travel of the said article, a rotatable and axially movable rod carrying the said target, a carriage connected to the said rod, article clamping dies carried by the said carriage, an article cutter movable across the line of travel of the article and intermediate the ends of the dies, and a stationary device having a reciprocating part operatively connected to the said cutter to move the same across the line of travel of the said article intermediate the ends of the dies.

8. Apparatus for severing moving articles, comprising means for forcibly impelling in an axial direction an article of indefinite length, in combination with flying cut-off mechanism for cutting successively predetermined uniform lengths from the end of the said article without interrupting the movement thereof, said mechanism including a target rotatable into and out of the line of travel of the said article, a rotatable rod movable in a direction parallel to the line of

travel of the article and carrying the target, the target being adjustably fixed on the rod, a carriage connected to said rod, article clamping dies carried by the said carriage, an article cutter movable across the line of travel of the article and a stationary device having a reciprocating part operatively connected to the said cutter to move the same across the line of travel of the said article.

10. 9. Apparatus for severing moving articles comprising means for forcibly impelling in axial direction an article of indefinite length, in combination with flying cut-off mechanism for cutting successively predetermined units 15 form lengths from the end of said article without interrupting the movement thereof, said mechanism including a target, means for moving the target into and out of the line of travel of the article, a movable carriage 20 connected to the said target and movable therewith in directions parallel to the line of travel of the article, article clamping dies on the carriage, an article cutter movable with the article and also movable transversely 25 thereof, a stationary press having a reciprocating head operatively connected to the said cutter to actuate the latter across the line of travel of the article intermediate the ends of the dies, and means operable after the cutter has severed the article for restoring the 30 said target and carriage to their initial positions.

10. A flying cut-off for axially moving metallic tubing comprising a stationary press 35 having a reciprocating head, a tube cutter movable with and relative to the said head, dies for clamping the tubing, means including the reciprocating head for moving the cutter across the tube at the point where the 40 tube is to be severed, means operatively associated with the said cutter and tube for transmitting axial motion of the tube to and moving the cutter relative to the said reciprocating head, and means operable during 45 the return stroke of the reciprocating head to its initial position for moving the said cutter relative to the head and opposite to the line of travel of the said tube to the initial or starting position.

50. 11. A flying cut-off for axially moving metallic tubing comprising a stationary press having a reciprocating head, a tube cutter movable with and relative to the said head, dies for clamping the tubing, a movable carriage supporting the said dies, means including the reciprocating head for moving the cutter across the tube at a point where the tube is to be severed, means including guide members carried by the carriage and 55 operatively associated with the said cutter for transmitting axial movement of the tube to and moving the cutter relative to the said reciprocating head, and means operable during the return stroke of the reciprocating head to its initial position for moving the said cutter 60 relative to the head and opposite to the line of travel of the said tube to the initial or starting position, the moving parts of the said fluid pressure means being automatically returned to their initial or starting position while the reciprocating head is stationary in its initial position.

cutter relative to the head opposite to the line of travel of the said tube to its initial or starting position.

12. A flying cut-off for axially moving metallic tubing comprising a stationary press 70 having a reciprocating head, a tube cutter movable with and relative to the said head, dies for clamping the tubing, a movable carriage supporting the said dies, means including the reciprocating head for moving the 75 cutter across the tube at a point where the tube is to be severed, means including guides supported by the said carriage and die closers carried by the head and operatively associated with the said cutter for transmitting movement thereof axially of the tube to and moving the cutter relative to said reciprocating head, and means operable during the return stroke of the reciprocating head to its initial 80 position for moving the said cutter relative to the head and opposite to the line of travel of the said tube to its initial or starting position.

13. A flying cut-off for axially moving metallic tubing comprising a stationary press 90 having a reciprocating head, a tube cutter movable with and relative to the said head, dies for clamping the tubing, means including the reciprocating head for moving the cutter across the tube at the point where the tube is to be severed, means operatively associated with the said cutter and tube for transmitting axial motion of the tube to and moving the cutter relative to the said reciprocating head, and fluid pressure means 100 operable during the return stroke of the reciprocating head to its initial position for moving the said cutter relative to the head and opposite to the line of travel of the said tube to the initial or starting position.

14. A flying cut-off for axially moving metallic tubing comprising a stationary press having a reciprocating head, a tube cutter movable with and relative to the said head, dies for clamping the tubing, means including the reciprocating head for moving the cutter across the tube at the point where the tube is to be severed, means operatively associated with the said cutter and tube for transmitting axial motion of the tube to and moving the cutter relative to the said reciprocating head, and fluid pressure means including moving parts operable during the return stroke of the reciprocating head to its initial position for moving the said cutter relative to the head and opposite to the line of travel of the said tube to the initial or starting position, the moving parts of the said fluid pressure means being automatically returned to their initial or starting position while the reciprocating head is stationary in its initial position.

15. A flying cut-off for axially moving metallic tubing comprising a stationary press 120

having a reciprocating head, a tube cutter movable with and relative to the said head, dies for clamping the tubing, means including the reciprocating head for moving the cutter across the tube at the point where the tube is to be severed, means operatively associated with the said cutter and tube for transmitting axial motion of the tube to and moving the cutter relative to the said reciprocating head, a cylinder having a piston operatively associated with the last said means, a multiple way valve connected to the said cylinder for admitting fluid under pressure into the latter to actuate the said piston in either direction and means carried by the said head for actuating the said valve, the cylinder, piston, valve and the last said means cooperating during the return stroke of the head to its initial position to move the cutter relative to the head and opposite to the line of travel of the said tube, and to return the cutter to its initial or starting position, these said parts cooperating after the said head has reached its starting position and while it is stationary therein for moving the piston to its starting position in the cylinder.

16. A flying cut-off for axially moving metallic tubing comprising a stationary press having a reciprocating head, a tube cutter movable with the said head across the line of travel of an axially moving tube and movable relative to the head in directions with and opposite to the travel of the said tube, dies on opposite sides of the said cutter and movable therewith, means for clamping the said dies about the tube during the movement of the cutter transversely across the tube, and means for restoring the cutter and the dies to their initial position.

17. A flying cut-off for axially moving metallic tubing comprising a stationary press having a reciprocating head, a tube cutter operatively associated with the said head and reciprocable across axially moving tubing to be severed, means movable in directions parallel to the line of travel of the said tubing and including dies adapted to clamp about the tubing, the said means being operatively associated with the said cutter for moving the latter relative to the said head, means actuated by the said tubing for actuating the dies, and fluid pressure means for moving the dies and cutter in the direction opposite the line of travel of the said tubing.

18. A flying cut-off for axially moving metallic tubing comprising a stationary press having a reciprocating head carrying a tube cutter movable therewith and relative thereto, a movable carriage having tube clamping means connected thereto, means for transmitting axial movement of the tube to be severed to the said carriage, and electrical means actuated by movement of the said carriage for causing the reciprocation of the said head.

19. A flying cut-off for axially moving

articles comprising a stationary press having a reciprocating head carrying an article cutter movable therewith and relative thereto, article clamping means, means for transmitting axial movement of the article to be severed to the said clamping means and electrical means actuated when the end of the article to be severed has travelled a predetermined distance beyond the cutter for causing a single complete stroke of the said head.

20. A flying cut-off for axially moving articles comprising a stationary press having a reciprocating head carrying an article cutter movable therewith and relative thereto, article clamping means, means for transmitting axial movement of the article to be severed to the said clamping means and cutter and fluid pressure means actuated when the said tube clamping means and cutter have traveled a predetermined distance for causing reciprocation of the clamping means and cutter to their initial positions in a direction opposite to the travel of the said article.

21. A flying cut-off for axially moving articles comprising a stationary press having a reciprocating head carrying an article cutter movable therewith and relative thereto, article clamping means connected thereto, means for transmitting axial movement of the article to be severed to the said clamping means and electrical means actuated by movement of the said carriage for synchronizing the reciprocation of the head and movement of the cutter relative thereto while the tubing is in motion.

22. A flying cut-off for axially moving articles comprising a stationary press having a reciprocable head, a cutter movable with the head transversely across an axially moving article to be severed and relative to the head longitudinally of the said article, means actuated by axial movement of the article for moving the head and the cutter relative to the head, and means actuated after the cutter has moved across and cleared the tube for moving the cutter to its initial position and relative to the head.

23. A flying cut-off for axially moving articles comprising a stationary press having a reciprocable head, a cutter movable with the head transversely across an axially moving article to be severed and relative to the head longitudinally of the said article, means actuated by axial movement of the article for moving the head and the cutter relative to the head, and fluid pressure means actuated by the head after the cutter has moved across the tube for moving the cutter to its initial position and relative to the head.

24. A flying cut-off for axially moving articles comprising a stationary press having a reciprocable head, a cutter movable with the head transversely across an axially moving article to be severed and relative to the head longitudinally of the said article, means ac-

tuated by axial movement of the article for moving the head and the cutter relative to the head, and fluid pressure means including a piston and cylinder operatively associated with the said cutter and actuated when the cutter has moved across and cleared the article for moving the cutter to its initial position and relative to the head.

25. A flying cut-off for axially moving articles comprising a stationary press having a reciprocable head, a cutter movable with the head transversely across an axially moving article to be severed and relative to the head longitudinally of the said article, means actuated by axial movement of the article for moving the head and the cutter relative to the head, a cylinder and piston operatively associated with the said cutter for moving the latter longitudinally in a direction opposite to the travel of the article, and a multiple way valve adapted to control the application of fluid pressure to the said cylinder and piston, said cylinder, piston and valve cooperating to move the cutter to its initial position and relative to the head after the cutter has moved across and cleared the tube.

26. A flying cut-off for axially moving articles comprising a stationary press having a reciprocable head, a cutter movable with the head transversely across an axially moving article to be severed and relative to the head longitudinally of the said article, means actuated by axial movement of the article for moving the head and the cutter relative to the head, a cylinder, a piston operatively associated with the cutter therein, and a multiple way valve operable by the said head after the cutter has moved across and cleared the article to admit fluid pressure into the said cylinder, to move the cutter to its initial position and relative to the head.

27. A flying cut-off for axially moving articles comprising a stationary press having a reciprocable head, a cutter movable with the head transversely across an axially moving article to be severed and relative to the head longitudinally of the said article, means actuated by axial movement of the article for moving the cutter relative to and with the head, a cylinder, a piston therein operatively associated through a lost motion connection with the cutter actuating means, and a multiple way valve operable when the cutter has moved across and cleared the article to admit fluid pressure into the said cylinder to move the cutter to its initial position and relative to the head and means for actuating the valve after the cutter has been returned to and while it is in its initial position to admit fluid pressure into the cylinder to return the piston to its initial position in the cylinder.

28. A flying cut-off for axially moving tubing comprising a stationary press having a reciprocable head, a cutter movable with the head transversely across an axially moving

tube to be severed and relative to the head longitudinally of the said tube, in and also opposite to the direction of travel of the said tube, means for causing reciprocation of the head and movement of the cutter transversely across the said tube, means for moving the cutter relative to the head in the direction of travel of the tube and at the same speed as the tube and fluid pressure means actuated after the cutter has severed and cleared the tube for returning the cutter to its initial position relative to the head and in a direction opposite to the direction of travel of the tube and longitudinally of the tube.

In testimony whereof I hereunto affix my signature this 1st day of November, 1927.

CARL A. BRAUN.
